UNITED STATES PATENT OFFICE.

CHARLES P. WHITE, OF GREENSBORO, NORTH CAROLINA.

RELIEF-VALVE.

1,023,187.

Specification of Letters Patent.

Patented Apr. 16, 1912.

Application filed September 13, 1910. Serial No. 581,899.

To all whom it may concern:

Be it known that I, CHARLES P. WHITE, citizen of the United States, residing at Greensboro, in the county of Guilford and 5 State of North Carolina, have invented certain new and useful Improvements in Relief Valves, of which the following is a specification.

This invention comprehends certain new 10 and useful improvements in relief valves for discharging from locomotive engine or other steam cylinders, the water of condensation automatically without any appreciable waste of steam under pressure, and the invention 15 has for its object a simple construction of valve of this character, the parts of which are few in number and not liable to get out of order.

With this and other objects in view as 20 will more fully appear as the description proceeds, the invention consists in certain constructions, arrangements and combinations of the parts that I shall hereinafter fully describe and claim.

25 For a full understanding of the invention, reference is to be had to the following description and accompanying drawings, in which:

Figure 1 is a longitudinal sectional view 30 of an engine cylinder equipped with my improved relief valves; and, Fig. 2 is an enlarged sectional view of the valve.

Corresponding and like parts are referred to in the following description and indicated 35 in all the views of the drawings by the same reference characters.

My improved relief valve comprises a body portion or case 1 which is preferably 40 interiorly threaded at one end to receive a nipple 2 which may be either straight or curved so as to connect the valve to an engine cylinder with the valve standing either in a vertical or a horizontal position. The casting 45 1 is provided at its end next to the nipple 2 with a condensation chamber 3 which is bounded on one side by a transversely extending partition 4 which separates the chamber 3 from the fluid outlet chamber 5, the latter being provided with an 50 outlet nipple 6, as clearly illustrated in the drawing. The fluid outlet chamber 5 is bounded on one side by the partition 4 and on its opposite side by a corresponding partition 7 separating said chamber from a cylindrical chamber 8 in which a piston 9 is 55 mounted. The adjoining end of the casing

1 is closed, as by the screw cap 10, and is provided, preferably at diametrically opposite points, with ports 11 leading into the chamber 8 on the lower or outer side of the piston 9. The piston is preferably formed with a nib 12 designed to abut against the screw cap 10 so as to limit the movement of the piston in one direction, such movement being stopped at a point before the piston 65 9 can close the ports 11.

The partition 4 is formed with a preferably beveled centrally disposed opening 13 designed to establish communication between the chambers 3 and 5, and said opening forms a valve seat for a normally closed turbinete valve 14. This valve is provided with guide stems 15 and 16, one of these being branched, as at 17, to work in the nipple 2, while the other stem (16) works 75 in an opening 18 formed in the partition 7 and passes through said opening into the chamber 8 where it is designed for engagement by the piston 9. In carrying out my invention, any desired number of the relief valves may be employed in connection with 80 the engine cylinder to be drained, and each valve is secured to the cylinder by a nipple such as indicated at 2, as hereinbefore stated. One of the ports 11 is piped to some source 85 of supply of fluid pressure under the control of the engineer in the locomotive cab for instance, while the other port 11 may either be plugged, if not desired for use, or may be used to connect its relief valve with others 90 like it.

From the foregoing description in connection with the accompanying drawing, the 95 operation of my improved relief valve will be apparent. The valve 14 is normally closed and is maintained in closed position so long as the engine is running. Whenever the engine stops, it is only necessary for the engineer to turn live steam or other fluid pressure into the chamber 8 underneath the piston 9, whereby the piston, by engagement with the guide stem 15 of the valve 14, will move said valve off of its seat 13, thereby establishing communication between the condensation chamber 3 and the fluid outlet chamber 5 and permitting the fluid to flow out of the latter. It will thus be seen that the cylinder can be kept practically free of water of condensation, all the space within the cylinder being maintained for the full 105 expansion of the steam.

Preferably, the screw cap 10 carries a

spring pressed drain valve 19, the stem of which preferably protrudes slightly, as shown, so that by pressing the valve 19, the relief valve case 1 may be drained of all 5 water that may have leaked out past the piston 9 or formed by the steam condensing in the chamber 8.

In the preferred arrangement of parts 10 the piping for one set of relief valves is connected to the piping for the other set of valves by a cross over pipe and coupling, such as that illustrated at 20 in Fig. 1. By 15 this means it will be understood that the relief valves of both engine cylinders may be controlled by a single pipe extending to the locomotive cab.

A port 21 is formed in the side wall of the cylindrical chamber 8 in such position that 20 it will be opened when the piston 9 is lowered and closed when the piston 9 is raised, and a second port 22 establishes communication between the chamber 8 and the fluid outlet nipple 6. By this means, there will 25 always be an outlet for condensed steam which may pass the piston in the operation of the device.

Having thus described the invention, what is claimed as new is:

1. A relief valve, comprising a casing embodying a condensation chamber, and a fluid outlet chamber, and a partition separating the two, said partition being formed with an opening designed to establish communication between said chambers, the opening 30 constituting a valve seat, a valve normally resting on the said seat to close the same, the valve being formed with oppositely extending guide stems, one of which is branched, for the purpose specified, the casing 35 being further formed with a piston chamber, and a partition separating the piston chamber from the fluid outlet chamber, said last named partition being formed with an opening in which the other guide stem is 40 mounted, said stem passing through said opening into the piston chamber, and a piston mounted in the piston chamber and arranged to engage said last named stem to 45

unseat the valve, the casing being formed with a port in the piston chamber, for the 50 purpose set forth.

2. A relief valve, comprising a casing embodying a condensation chamber and a fluid outlet chamber, a partition separating the two, the partition being formed with a 55 valve seat adapted to establish communication between said chambers, a valve resting on said seat and normally closing the same, the valve being formed with a guide stem, the casing being further provided with a 60 piston chamber and a partition separating the latter from the fluid outlet chamber, the guide stem of the valve passing through said piston chamber and a screw cap secured to the casing and 65 closing said piston chamber, and a piston mounted in said chamber and adapted to engage the guide stem of the valve to unseat the latter, the piston being formed with a nipple adapted to engage the screw cap, 70 for the purpose specified, the casing being formed in the piston chamber with a port for the inlet of fluid pressure.

3. A relief valve comprising a casing embodying a condensation chamber and a fluid 75 outlet chamber, a partition separating the two and formed with a valve-seat, the said valve embodying also a piston chamber, a cap adjustably threaded into the lower end of the piston chamber, a valve resting normally upon the valve seat in the partition 80 between the condensation and fluid outlet chambers, the valve having a stem projecting through the upper end of the piston chamber, a piston within the piston chamber 85 against the upper face of which the lower end of the valve-seat rests, and a nipple upon the under side of the piston resting upon the cap.

In testimony whereof, I affix my signature 90 in presence of two witnesses.

CHARLES P. WHITE. [L. S.]
